UNITED STATES PATENT OFFICE.

JESSE THOMAS CAMPBELL, OF ELBRIDGE, TENNESSEE.

GUN EMPLACEMENT OR FORT.

1,314,466.

Specification of Letters Patent. Patented Aug. 26, 1919.

Application filed November 12, 1918. Serial No. 262,209.

To all whom it may concern:

Be it known that I, JESSE THOMAS CAMPBELL, a citizen of the United States, residing at Elbridge, in the county of Obion and State of Tennessee, have invented a new and useful Gun Emplacement or Fort, of which the following is a specification.

The subject of this invention is a gun emplacement or fort.

10 The main object of the invention is the provision of means for handling a large number of guns with few attendants.

Another object of the invention is the provision of means for firing the guns singly or 15 in unison.

Another object is the provision of means for training a number of guns in one direction.

Still another object of the invention is the 20 provision of means for elevating the guns for high angle firing.

The invention also contemplates generally improving the construction and enhancing the utility of gun emplacements.

25 With the foregoing and other objects in view, which will appear as the description proceeds, the invention resides in the combination and arrangement of parts and in the details of construction hereinafter described

30 and claimed, it being understood that changes in the precise embodiment of the invention herein disclosed can be made within the scope of what is claimed without departing from the spirit of the invention.

35 Practical structures for carrying out the invention are illustrated in the accompanying drawings, wherein:—

Figure 1 is a view in elevation of an emplacement constructed in accordance with 40 the invention, a portion shown in section;

Fig. 2 is a diagrammatic plan view of the device, the dome being in section;

Fig. 3 is an enlarged detail view in side elevation, partly in section, of a gun mount;

45 Fig. 4 is a plan view of the same;

Fig. 5 is an enlarged detail view in central, vertical section of a gun mount pedestal;

Fig. 6 is a plan view of the firing mechanism;

Fig. 7 is a plan view showing in fragmentary detail the manual means for actuating the gun mount gearing;

Fig. 8 is a plan view of a modified form of 55 gun mount;

Fig. 9 is a side elevation of the same;

Fig. 10 is an enlarged detail view in longitudinal section of a firing pin and its casing;

Fig. 11 is a plan view of a firing device 60 for selective electric firing;

Fig. 12 is a view in elevation, partly in section, of the same.

Referring to the drawings by numerals of reference:—

In carrying out the invention a dome like shell 1 is provided, which is preferably made of armor plate steel, and it may be formed with an outwardly projecting annular flange 2 situated at its base. The shell 1 is seated 70 on a base 3 of concrete or the like, and concrete is poured about the shell to a sufficient height to form a retaining wall 4 which overlies the flange 2 and anchors the shell firmly in place. An observation dome or tower 5 75 is provided at the top of the shell 1 to permit the operator or attendant to gain a view in all directions.

Spaced circumferentially of the shell 1 are the alternate gun ports 6 and 7, the ports 80 7 being of slightly greater depth than the ports 6 so that the guns in the ports 7 may be elevated to a greater angle for the purpose of repelling attacks from air craft. The ports 7 alternate with the ports 6 so 85 that the space through which projectiles might find entrance to the structure may be reduced to a minimum, consistent with the proper operation of the device.

The floor space within the shell is divided, see Fig. 2, into a circular path 8 which permits the attendant free access to the guns for the purpose of loading and the like, and within this circular track is an ammunition space 9. At the center a circular 95 space is provided for the accommodation of the attendant or attendants operating and firing the guns, as indicated at 10.

Secured to the floor 3 in any usual manner adjacent each port 6 and 7 is a pedestal 11, 100 from the base of which rises an annular flange 12 the upper edge of which forms a track for rollers 13, which support a gun-mount 14 and engage in a groove formed annularly of the base thereof. The mount 14 105 is also journaled in the pedestal 11 at 15 to secure the mount against lateral thrust.

For the purpose of rotating the mount about its vertical axis, and so providing for aiming the gun in various directions, an annular worm wheel or ring 16 is secured to the mount and the teeth of this worm wheel 110

mesh with the threads of a worm 17 which is journaled in a bracket 18, suitably secured to the pedestal 11. An operating rod 19 is provided for rotating the worm, and one end of this rod is universally jointed, as at 20, to the worm shaft, while the opposite end of the rod is journaled in a standard 21, located convenient to the operator, and upon this end of the rod is rigidly affixed a hand wheel 22 by which the rod may be manually rotated.

Supported in the mount 14 to rock on trunnions 23, which are suitably journaled in the mount, is a cradle 24 in which the guns 25 are supported. While only three guns have been shown herein to a cradle it is to be understood that the invention is not confined to any particular number of guns to a mount.

20 Rising from the front end of the cradle 24, and preferably integral therewith, is a lug 26 to which is secured the forward end of the recoil cylinder 27. Rising from the rear end of the cradle 24, and positioned at each side of the recoil cylinder 27, are lugs 28, 29, against which the rear ends of the spring cylinders 29 abut. The spring cylinders are of the usual type and serve to return the guns to battery after the recoil thereof.

25 The breech ends of the guns 25, which project rearwardly of the cradle 24, are secured together by a yoke 30, from which rises a flange 31, apertured to receive the rear ends of the piston rods of the recoil and spring cylinders, which rods are secured to the flange by any suitable means, such as the nuts 32.

In order that the cradle may be rocked upon its trunnions to elevate the guns to desired angles, a segmental rack 33 is secured to and depends from the cradle 24. The teeth of the rack 33 are in mesh with a worm 34, which is suitably journaled in the gun mount 14. The worm 34 has rigidly affixed thereto a beveled pinion 35, which meshes with a similar pinion secured to the upper end of a vertically disposed shaft 36, which is journaled in a standard 36' secured within the pedestal 11. The axis 50 of the shaft 36 is coincident with the axis of rotation of the mount 14, so that the beveled pinions are in mesh at all positions of the mount. The shaft 36 has a beveled pinion rigidly secured to its lower end which meshes with a like pinion 37, rigid on one end of a shaft 38, the other end of which is connected by a universal joint 39 to an operating rod 40. That end of the rod 40 remote from the joint 39 is journaled in the standard 21, and is provided with a hand wheel 41, by which the rod may be manually rotated.

Provision is made for firing the guns on a mount either singly or in unison, and a practical structure for carrying out this

feature of the invention is shown in Figs. 2 and 6. Supports or standards 42 are secured to and rise from the floor 3, and these standards are apertured to receive rods 43 with a smooth sliding fit. Each rod 43 has spaced apertures formed therein for the reception of pins 44 and 44', the former of which is placed in that aperture lying between the supports 42, and these pins serve to limit the movement of the rods 75 through the supports. The forward ends of the rods 43 are formed with eyes in each of which is connected one end of a wire 45, the other end of which is roughened and embedded in a friction priming 46, in 80 the usual manner. These wires may also be connected to other charge exploding or igniting means, if desired. Each rod is provided with an operating handle 45' by means of which the rods may be separately 85 actuated to fire the respective guns.

To provide for operating the rods in unison so that the guns may be fired simultaneously, a cross bar 47 is slidable on the rods 43 and is apertured so that the rods pass therethrough. This cross bar is positioned between the supports 42 and forwardly of the pins 44. An operating rod 48 is rigidly connected to the cross bar 47 and is slidable through apertures formed in the supports 42, and this rod has a handle 48' secured to its rear end by which the rod may be actuated. When the rod 48 is drawn rearwardly, it draws the cross bar 47 with it, and the cross bar engages 100 the pins 44 thereby causing the rods 43 to move rearwardly in unison and the guns to be simultaneously fired.

In the modification illustrated in Figs. 8, 9 and 10, the gun mounts comprise a platform 50, which is supported on the flanged rollers 51 adapted to run on the spaced, arcuate tracks 52, which tracks are secured to the flooring. A bracket 53 extends rearwardly from the platform 50, to which it is secured, and in this bracket is journaled a reducing gear train 54, one end member of which train meshes with the teeth of an arcuate rack 55, also secured to the floor at the rear of the track 52. An operating 110 rod or shaft 54' is rigidly connected to that gear wheel of the train 54 situated at the end of the train remote from the end wheel which meshes with the rack, and a hand wheel may be rigidly connected to this rod 120 for the purpose of rotating the same and actuating the gear train to move the platform along the track.

Adjacent each side of the platform 50, and rising from the upper face thereof, is a flange or tongue 56, which extends longitudinally of the platform and which enters a groove formed in the bottom of the gun carriage 57, the carriage being mounted on the platform and slide longitudinally 130

thereof. A recoil cylinder 58 is suitably secured on the platform 50, rearwardly of the carriage 57, and the piston rod of this cylinder is connected to the carriage in any 5 suitable manner. Likewise secured on the platform 50, and at each side of the recoil cylinder 58, is a spring cylinder 59, the respective piston rods of which are connected to the carriage 57. These cylinders have the 10 usual action of such mechanism, as heretofore set forth.

Rockable on trunnions 60, which are suitably journaled in the yoke of the carriage 57, is a cradle 61 in which the small caliber 15 guns 62 are supported. These guns are preferably firmly yoked or bound together by the cradle, as shown. Each gun is, when to be fired, supplied with a primer 63, and each gun may be fired singly by manipulation 20 of the rods 71, or in unison by the rod 72, as heretofore set forth in relation to the rods 43 and 48.

When it is desired to fire the guns by means of percussion primers, the device 25 illustrated in Fig. 10 may be made use of. This consists in a casing 64 in the longitudinal bore of which a firing pin 64' is slidably mounted. This pin is normally held in its forward position by means of a compression 30 spring 65. A lug or pin 66 extends radially from the pin 64', at a position between the ends of the pin 64', and the lug is normally engaged by the upper end of a trigger 67, which is pivotally mounted in the casing 64. 35 The trigger 67 is formed with a ruler joint 68, and is held in normal position by a retractile spring 69, so that, when the trigger is pulled by the connector or firing device 70, which is threaded through an aperture 40 formed in the casing 64, it will swing upon its pivot and carry the firing pin rearwardly against the tension of the spring 65. When the firing pin has moved rearwardly a sufficient distance, the trigger 67 will pass 45 the lug 66 and release the firing pin to move rapidly forwardly under the expansive force of the compression spring 65. When pull on the firing device 70 is released, the retractile spring 69 will draw the trigger to 50 normal position, the ruler joint allowing the upper part of the trigger to click past the lug 66.

To provide means for elevating these guns a T standard 74 is secured to and rises from 55 the rear of the platform 50, and is arranged with its cross arm extending longitudinally of the platform. To the forward end of the cross arm of the standard is pivotally connected the lower end of a link 75, while to the rear end of the cross arm is pivotally connected, between its ends, a lever 76, the lower end of which is provided with a hand grip 77 and the upper end of which has pivotal connection with one end of a connecting 60 rod 78, the other end of which rod is pivot-

ally connected to the upper end of the link 75. The link 75 is provided, between its ends, with a laterally extending pin which engages in a slot formed longitudinally of the rear end of a connecting rod 79, the forward end of which rod has pivotal connection with a crank arm 80, rigidly secured to the cradle 61. The purpose of the slot and pin connection between the rod 79 and the link 75 is to permit play to allow for the 75 recoil of the guns.

In order that electrical firing of the guns singly or in unison may be provided for, the structure shown in Figs. 11 and 12 may be provided. Supports 81 are provided to 80 which are pivotally secured the ends of a pair of arms 82, which are connected by and formed integral with the cross bar 83. An arm 84 rises from the cross bar 83 and at the upper end of this arm is provided a push 85 button 85. The cross bar 83 is normally held in elevated position by the compression springs 86, which springs should be of considerable tension. Individual push buttons 87 are provided with slots for the reception 90 of the cross bar 83, on which these buttons are mounted for vertical motion independent of the cross bar. Light compression springs 89 are positioned in the slots of these buttons and are confined between the upper 95 ends of the slots and the cross bar to normally hold the buttons in elevated positions. A bridging piece 90 is secured to the lower end of each of these buttons 87, and serves to bridge the terminals of the leads or conductors 91, which normally form an open 100 circuit between the electric igniter and a suitable source of electric current supply.

It is to be understood that the gun mounts herein shown, while illustrated as mounted 105 on a stationary floor or platform, may be mounted on a suitable rotary or other movable platform, if so desired.

The foregoing description having amply set forth the operation of the device, a special and extended explanation thereof will 110 not be here given.

Having described the invention, what is claimed as new is:—

1. The combination with a stationary 115 dome-like shell having elongated gun ports therein, there being a central space within the shell constituting a control station, of a pedestal within the shell and back of each port, a gun mount arranged for rotation on 120 each pedestal, guns on the mounts and projecting into the ports, means extending into the control station from all the mounts for independently rotating the mounts, means extending into the control station for independently elevating the guns on their mounts, and means extending into the central control station for separately or simultaneously 125 firing the guns.

2. A gun emplacement including a pedes- 130

tal, a downwardly tapered gun mount projecting into and revoluble within the pedestal, a worm gear extending around the gun mount, a worm engaging said gear for 5 rotating the gun mount, a standard mounted on the bottom of the pedestal and extending into the gun mount, said standard being stationary, a cradle hung within the gun mount, a segmental gear movable there-
10 with and extending over the gun mount, a worm on the gun mount engaging the segmental gear, a shaft journaled in the stationary standard, there being an elongated

slot in the gun mount through which the shaft extends, and gearing within the gun 15 mount for transmitting motion from the said shaft to the worm engaging the segmental gear.

In testimony that I claim the foregoing as my own, I have hereto affixed my signature 20 in the presence of two witnesses.

JESSE THOMAS CAMPBELL.
